UNITED STATES PATENT OFFICE.

ARTHUR M. ALLEN, OF BROOKLYN, ASSIGNOR, BY MESNE ASSIGNMENTS,
TO LEONORA L. ALLEN, OF NEW YORK, N. Y.

WHEEL.

SPECIFICATION forming part of Letters Patent No. 278,071, dated May 22, 1883.

Application filed March 8, 1882. (No model.)

To all whom it may concern:

Be it known that I, ARTHUR M. ALLEN, a citizen of the United States, residing at Brooklyn, in the county of Kings and State of New York, have invented new and useful Improvements in Wheels or Pulleys, of which the following is a specification.

This invention is adapted to wheels for carriages or other vehicles, to paddle-wheels for steamboats, and also to pulleys for machinery; and it consists in the novel construction and arrangement of parts hereinafter described, whereby a true circular rim is maintained, a superior elasticity is produced, tending to 15 counteract the torsional action upon the wheel, and one which is capable of graduation, similar parts are rendered interchangeable or capable of renewal, and the manufacture as well as repair of the article is facilitated or cheapened.

This invention is illustrated in the accompanying drawings, in which Figure 1 is a side view, showing the wheel set up. Fig. 2 is a sectional view on the line $x-x$, Fig. 3. Fig. 3 is a vertical central cross-section. Fig. 4 is a 25 sectional view of the hub, showing the position of the spokes before the wheel is set up. Fig. 5 is another section thereof, together with the brace-disks. Fig. 6 is a view corresponding to Fig. 5, but omitting the hub. Fig. 7 is a cross-section on the line $y-y$, Fig. 5. Fig. 8 is a cross-section of the inner rim, showing the connections of the braces. Fig. 9 is a similar 30 section of the outer rim, showing the manner of securing thereto the suspension-strap. Fig. 35 10 is a longitudinal section of one of the braces, showing its joint.

Similar letters indicate corresponding parts.

The letter A designates a cylinder, which 40 carries a hub, B, at about its mid-length, together with two disks, C, one on each side of the hub, the hub being fixed, as by a feather-key, and the disks being loose. In this example the cylinder A is hollow and forms an axle-box; but it can also be made solid, in which case it is provided with journals.

The preferred method of forming the cylinder A when it is hollow is to cast the same inside of the hub B and disks C, and over a 45 finished axle, so that the wheel is ready for use when it is "set up."

In the periphery of the hub B are mortises u , having inserted therein the inner ends of spokes D, the outer ends of which are fitted into suitable cavities in a rim, E, the spokes 55 being shouldered near the outer ends, forming tenons. The mortises u are larger in the direction of the circumference of the hub than the thickness of the spokes, and in setting up the wheel the spokes are set aslant or tangential to the hub, with their inner extremities upon the base and at one end of the mortises, as shown in Fig. 4, and the rim E having been fastened stationary in a suitable frame, the hub is turned by a suitable tool in the direction indicated in 60 Fig. 4 until the spokes assume a radial position, their inner ends being thus made to abut against the base of the mortises and their outer shouldered ends against the rim. The mortises u are then entirely closed up by means of filling- 65 pieces t , Fig. 2, prepared for this purpose, and in this manner the spokes are held rigid and in proper relation both to the hub B and the rim E, thereby acting upon the latter with uniformity and preserving or maintaining its true circular 70 shape. The spokes D can also be fastened or held in their radial positions by means of braces or tie-rods. The spokes D can be made either of wood or metal, and a packing of india-rubber or other suitable material may be placed in a 75 groove at the base of the hub - mortises u , to compensate for any deficiency in the length of the spokes due to wear or to any possible error in their manufacture. The filling-pieces t are made of an elastic material—as india-rubber— 80 thus forming cushions, or of a hard substance— 85 as wood—and they may be secured in position by screws or other suitable means.

To the disks C respectively is connected one of the ends of braces F, the other of whose 90 ends is connected to the rim E. These braces are composed of metallic rods, and in this example the connection thereof with the rim E is effected by means of heads q , at the outer ends of the braces, entering suitable recesses 95 in the rim, and with the disks by means of loops p , at the inner ends of the braces, entering suitable recesses in the peripheries of the disks and engaging with bolts o . When the wheel is to be set up the disks C are turned in 100 opposite directions by a suitable contrivance a sufficient distance to tighten the braces F,

making the same tangential to the disks. The disks are then fastened, and by the ensuing strain upon the rim E it is re-enforced to a material extent.

5 With the disks C are combined toggles G, which are entered into recesses s in the sides of the hub and in the inner surfaces of the disks, and which are placed in a diagonal position before turning the disks, the disks being 10 at this stage in an inner position upon the axle-box, so that when the disks are turned these toggles take a straight position, or one parallel to the axis of the wheel, where they are locked by brace-blocks v, (one or more,) placed between two of the toggles, or by other suitable devices. As the toggles G become straightened they force the disks C outward to the ends of the cylinder A and against stop-flanges r, formed upon the cylinder at those points, and 15 the effect of such movement of the disks is, like the rotary movement thereof, to strain or tighten the braces F, besides bringing the same to an inclined position from the disks to the rim E. Hence either the rotary movement 20 or the outward movement of the disks C can be utilized for tightening the braces F; or, in other words, the disks can be arranged either to turn or to spread outward without turning, the toggles G being used in the case last 25 named. Another method of arranging the disks C when they have spread is to secure one disk rigidly to the cylinder, leaving the other loose, so that the loose disk is caused to recede from the other or fixed disk by the toggles. When the disks C are arranged to turn 30 only, a pawl and ratchet or other contrivance can be used, in lieu of the toggles G and brace-blocks v, to fasten or retain the disks in their 35 positions.

40 The hub B and disks C, with their concomitants, can be used independently of each other, and in case the hub is omitted the toggles G are made to extend from disk to disk, as shown in Fig. 6, and a single brace-block only is required. The flanges r can also be used for 45 holding the hub B in position on the cylinder A when it is used alone, the hub being in that case made of equal length to the cylinder.

When the hub B is used and the toggles G 50 engage the same, as before stated, the spreading or outward movement of the disks C is produced by the action of the hub upon the toggles in turning the hub, for the purpose of radializing the spokes.

55 In the braces F respectively is arranged a spiral spring, n, preferably near one end thereof, in such a manner that such spring is a constituent part of the braces, and by this means the braces are rendered elastic in a longitudinal direction, allowing the same to yield not only to the action of their tension devices, but also to the torsional action upon the wheel. By straining the braces F to a greater or less extent their elasticity, due to the spring n, can 60 be graduated. The braces F are extensible or adjustable lengthwise, so that they can be permitted to take a greater or less degree of tan-

gency to the disks C, and to this end the braces are respectively made in two parts or sections, which overlap each other at their adjoining ends, and are provided with teeth l upon their opposed surfaces, whereby they engage each other, forming a toothed lap-joint, and a sleeve, k, is fitted upon the braces, so that if this sleeve is moved opposite to such joint the brace-sections are firmly locked in their positions, while when the sleeve is moved away from the joint onto either brace-section different teeth can be brought into engagement with each other, varying the length of the braces. A bayonet- 75 joint or other suitable device is used for holding the sleeve k in its locking position. The rim E is composed of a felly and tire, but can as well be made in one piece, and either tubular, angular, V-shaped, or U-shaped. 80

Surrounding the rim E is a secondary rim, E', which is connected to the first or inner rim concentrically therewith by means of an elastic suspension-strap, H, preferably composed of india-rubber. This strap H is continuous, 90 and is bent longitudinally in what may be termed a "zigzag" course, so as to meet or impinge against both rims E E', while at its points of contact it is secured to the rims by clamping-screws j or other suitable means. By the 95 zigzag shape and continuity of the suspension-strap H it is rendered elastic both in a longitudinal and lateral direction, at the same time possessing the required strength. The outer rim, E', is made T-shaped in cross-section for 100 rigidity, and in order to adapt the suspension-strap H to such shape thereof the strap is slotted at the points where it meets the rim, its slots allowing the strap to clear the shank of the T. 105

To the outer rim, E', is applied a peripheral sand-pad, I, whose covering is composed of a strip of leather or other similar material bent under the rim and secured thereto at or near its edges. The functions of this pad I is to 110 render the wheel adhesive and quiet in vehicular use, and to produce an increased friction when the article is used as a pulley.

It is evident that the outer rim, E', can be omitted, and in that event the sand-pad I may 115 be applied to the inner rim.

The casting of the cylinder within the wheel-hub is an important feature of my invention, and I reserve the right to make such feature the subject-matter of a separate application 120 for Letters Patent.

What I claim as new, and desire to secure by Letters Patent, is—

1. The combination, substantially as hereinbefore set forth, of the mortised hub B, the spokes D, the rim E, and the filling-pieces t, for the purpose specified. 125

2. The combination of the cylinder A, having flanges at its outer ends, the hub B, arranged on said cylinder, the disks C, arranged inside the flanges on the cylinder, and connecting devices between the disks and the hub, substantially as described. 130

3. The combination of the cylinder A, having

flanges at its outer ends, the mortised hub arranged on the cylinder, the rim E, the spokes D, secured in the hub and rim, the disks c, arranged inside the flanges on the cylinder, connecting devices between the disks and the hub, and braces F, connecting the disks with the rim, substantially as described.

4. The combination, substantially as herein-before set forth, of the cylinder A, the disks C, the braces F, the rim E, the toggles G, and toggle-locking devices, for the purpose specified.

5. The combination, substantially as herein-before set forth, of the cylinder A, flanged at its opposite ends, the disks C, braces F, rim E, toggles G, and toggle-locking devices, for the purpose specified.

6. The combination, substantially as herein-before set forth, of the cylinder A, the hub B, the disks C, the braces F, the rim E, the toggles G, and toggle-locking devices, for the purpose specified.

7. The combination of the cylinder A, the disks C, mounted on the ends thereof, the hub B, the rim E, the spokes D, secured to the rim and hub, and the braces F, provided with springs n, and connecting the rim with the disks, substantially as described.

8. The combination of the cylinder A, the disks C, mounted on the ends thereof, the rim

E, and the braces F, connecting the disks with the rim, and each made in two parts, so that their length can be adjusted, substantially as described.

9. The combination, substantially as herein-before set forth, of the disks C, the rim E, and the braces F, constructed in sections, which are united by a toothed lap-joint and sleeve for rendering the braces extensible.

10. The combination, substantially as herein-before set forth, of the rigidly-supported inner rim, E, the outer rim, E', and the continuous suspension-strap H, made of india-rubber and alternately connected to each rim.

11. The combination, substantially as herein-before set forth, of the cylinder, the rotating disks, the disk-locking devices, the rim E, and the two sets of braces F, each having its members connected to the disks and the rim independently of each other, whereby said members are permitted to assume tangential positions to the disks, and caused to preserve a like tangential angle thereto.

In testimony whereof I have hereunto set my hand in the presence of two subscribing witnesses.

ARTHUR M. ALLEN.
